SUPPORT

Walter J. Gamin, Garden City, N. Y.

Application January 10, 1947, Serial No. 721,401

6 Claims. (Cl. 211—87)

1

The invention relates to supports and has as an object to provide means to support containers, as spice cans, for ready access by the user.

It is an object of the invention to provide a support of the character referred to that may be attached to a vertical surface or to the underside of a shelf, as in a kitchen, to hold containers in readily accessible position.

It is a further object to provide a support of the said character that may be constructed from metal stampings at little cost.

It is a further object of the invention to provide a support for containers, as spice cans, formed for easy grasp of the containers for removal and for ready insertion.

It is a further object of the invention to provide a form of the invention for revoluble support whereby any one of a considerable number of containers may be made readily accessible.

Further objects will appear from the following description, when read in connection with the accompanying drawings disclosing illustrative embodiments of the invention and wherein:

Figure 1 is a plan view partly broken away of a structure of the invention ready for application to a supporting surface;

Fig. 2 is a vertical section on line 2—2 of Figure 1;

Fig. 3 is a view similar to Fig. 2 of the form of the invention shown in Fig. 1 showing another means of suspension;

Fig. 4 is a plan view of a lock washer utilized in the structure of Fig. 3;

Fig. 5 is a perspective view of one element used in the make-up of the structure of Figs. 1, 2 and 3;

Fig. 6 is a plan view of a blank from which the structure of Fig. 5 may be formed;

Fig. 7 is a view similar to Figure 1 of a still further form of the invention;

Fig. 8 is a side elevation of the structure of Fig. 7;

Fig. 9 is a section on line 9—9 of Fig. 7;

Fig. 10 is a detail horizontal section on line 10—10 of Fig. 9;

Fig. 11 is a perspective view of an element of the assemblage of the structure of Figs. 7 and 8;

Fig. 12 is a plan view of a blank from which the element of Fig. 11 may be formed.

Fig. 13 is a perspective view of a form of element having certain advantages over those referred to above; and

Fig. 14 is a plan view of a blank for the structure of Fig. 13.

As shown, the form of the device of Figures 1, 2 and 3 comprises a plate or disk 15, 15' shown

2

as circular in outline to which a plurality of elements 16 or 16' of the form shown in Figs. 5 or 13 may be secured in any desired manner as by soldering or brazing. A sufficient number of elements 16 or 16' are desirably applied to the disk to utilize the entire area of the disk at least so far as an outer zone thereof is concerned. The elements 16, 16' are shown as applied to the disk 15 with their fold lines so spaced as to provide an opening 18 between the wings 65 or 65' of the elements of the correct width to receive a usual size of spice can if the device is utilized to hold spice cans. To hold the fold edges 17 in correctly spaced position, recesses 19 are shown in Figures 2, 3 and 4 as provided in such edges into which a ring 20 is seated and secured as by soldering.

To secure the assembled device to the lower surface of a cabinet shelf for instance, if the shelf is of metal, the provision shown in Fig. 2 may be adopted. As there shown, a channel member 21 with overhanging lips is secured to the shelf by means of a screw 22. A rod 23 which forms a portion of the assemblage is assembled with a disk 15 by means of a block 24 through which a reduced portion of the rod 23 extends, said reduced portion providing a shoulder with contact with the block.

A supporting plate 25 is shown as secured upon the upper end of the rod 23 as by upset of a still further reduced portion of the rod 23, whereupon plate 25 is slipped into the channel plate 21 in the manner shown in Fig. 2 by which means of suspension the disk 15 carrying the assemblage and the containers housed therein may be revolved for ready access to a desired container.

In Fig. 3, there is shown means for attaching the assemblage to a wooden shelf in which form a rod 23' is secured to a supporting plate 26 which in turn is secured to the shelf by screws 27. The rod 23' seats in a sleeve 28 secured to the center of the disk 15' and the assemblage with the disk 15' may be secured upon the rod 23' by use of a slotted washer 29 such as shown in Fig. 4 slipped over a reduced portion of the rod 23'.

The elements 16 are adapted to be formed of a blank 30 of the form shown in Fig. 6, folded upon dotted line 31, a perforation 31 being provided to constitute the recess 19, when the blank is folded. Wings 32 may be turned up to provide shelves as shown in Fig. 5 upon which the containers may rest and displacement of the containers from the spaces 18 is prevented by

3
lips 33 provided on the element 16 at the ends of the shelves as shown.

The form of the device shown in Figs. 7 to 11, inclusive, is particularly designed to be mounted upon a wall or other vertical surface. For this use, the device is preferably made semicircular and comprises an upper plate 34 formed with a down turned margin 35 at its wall engaging side. To support the device upon a vertical surface a supporting plate 36, Fig. 10, is fastened to the wall by means of a screw 37 and the margin 35 is formed with a cutaway portion to provide the exposed edges 38, 39 to enter the ways provided by the offset edges of the plate 36.

As shown, the screw threaded opening 39' is formed in the plate 34 to receive a rod 40 upon which may be mounted an egg timer 41 of the hour glass type.

In the form of the device of Figs. 7 to 12, inclusive, each element 42 provides of itself a chamber for reception of the containers to be supported.

As shown in Figs. 11 and 12, the element 42 may be formed of the blank of Fig. 12 by folding the blank upon the lines 43, 44 to provide the spacing of the side walls 45, 46 and the shelves 47, 48 are formed by the corresponding portions of the blank of Fig. 12. Also the lips 49, 50 are provided in much the same manner as in the forms first described.

In this form of the device, the shelves 47, 48 are desirably so formed as to slope upwardly toward the opening of the chamber which slope is provided by the slight angle of the fold lines 51, 52 in the manner shown in Fig. 12.

In both forms of the device, the edges of the walls of the chamber as 45, 46, Fig. 11, are formed upon arcs to permit of ready grasp of the container housed in the chamber.

In the form of Figs. 7 to 12, the upper edges of the walls 45, 46 as well as the upper edge of the rear wall 53 are formed with tabs 54, 55, 56 to enter openings in the plate 34 wherein the tabs may be secured as by solder in the assembly of the device. If preferred, the tabs referred to may be made of sufficient length to extend through the opening in the plate 34 and may be secured therein by merely bending them over the upper surface of the plate.

In Fig. 13 is shown a form of element 16' similar to the embodiment of Fig. 5. The element 16' may be produced from the blank of Fig. 14. As shown in Fig. 13, shelves 32' and tabs 33' are provided as in Fig. 5. Ears 60 are formed on the wings 65' of the element 16' for convenience in soldering, welding or riveting to a plate as 15 or 34.

It is believed to be quite obvious that the forms of winged elements shown in Figs. 5, 11 and 13 are equivalents and either form may be used with the disk or plate 15, 15' or with the plate 34. The use of the various forms with the plate or disk 15, 15' or the partially circular plate 34 is merely for purpose of illustration. To provide a separate figure showing each form of winged element with each form of disk or plate seems purely a work of supererogation, multiplying the number of figures to no useful end.

The element 16' is shown as cut away at the

upper portion of its wings, at 61, 62 to provide an equivalent for the recesses 63, 64 of Fig. 5, the purpose of which structure being to enable ready grasp of a container for its removal and replacement.

Minor changes may be made in the physical embodiments of the invention within the scope of the appended claims without departing from the spirit of the invention.

I claim:

1. A support for a plurality of containers comprising, in combination: a plate; a plurality of pairs of container supporting wing members secured at the upper edge of each to said plate to be suspended therefrom in arcuate assemblage; individual wings of the pairs standing in parallel spaced relation to an adjacent wing; the lower edge of each wing formed with a container supporting shelf member; whereby to support each 10 one of a plurality of containers in a space between the wings, for ready removal; and means to secure said plate to a supporting structure.

2. The structure of claim 1 in which the plate is formed with its entire margin bounded by an 15 outwardly curved contour.

3. The structure of claim 1 in which the plate is a substantially circular disk and is mounted on the supporting structure for free revolution.

4. The structure of claim 1 in which the plate 20 is substantially semicircular; and formed with a rectilinear margin extending at an angle of substantially 90° to its body, said margin for attachment to a vertical surface.

5. The structure of claim 1 with pairs of said 25 wing members integral at a fold line wherefrom the wings of a pair radiate; said fold line formed with a recess; and a ring member secured in the respective recesses of an assembly of said wing members to retain the pairs in container receiving spaced relation.

6. The structure of claim 1 in which the plate is a circular disk and in which the arcuate assemblage comprises a substantially full circle; in combination with means for revolubly supporting the disk and assemblage from the lower surface of a supporting member; said means comprising a supporting plate to be secured to said surface; a rod depending from said supporting plate; a sleeve depending from said disk revoluble on said rod and support means carried by said rod to revolubly support said sleeve.
